For J. W. Beadle Atty

United States Patent Office.

J. L. W. TOWNSEND, OF MOUNT BLANCO, OHIO.

Letters Patent No. 91,183, dated June 8, 1869.

IMPROVEMENT IN YOKES.

The Schedule referred to in these Letters Patent and making part of the same.

To all whom it may concern:

Be it known that I, J. L. W. TOWNSEND, of Mount Blanco, in the county of Meigs, and State of Ohio, have invented a new and useful Improvement in Yokes; and I do hereby declare that the following is a full and exact description of the same, reference being had to the accompanying drawings, and to the letters of reference marked thereon.

This invention relates to a device for preventing cattle from jumping or breaking down fences, &c.; and consists of certain details of construction, which will be more fully described, hereinafter.

In the drawings—

Figure 1 is a perspective view of my invention;

Figure 2, a similar view of my invention attached to an animal; and

Figure 3, a perspective view of the key *a*.

To enable others skilled in the art to make and use my invention, I will now proceed to describe its construction and operation.

A represents the bow, which passes over the animal's neck, and is suitably attached to the block *B*.

The bow *A* is provided with a key, *a*, extending across the same sufficiently far down to admit the neck of an animal. This key is constructed substantially as shown in fig. 3, with an enlarged head, *a'*, and neck *a²* on one end, and the neck *a³* and head *a⁴* on the other, the head *a⁴* being at right angles with the main part of the key and the head *a'*.

C represent rods or pokes, which extend outward from the front of the block *B*, which latter is provided, on its rear sides, with the spikes or brads *b*.

It will readily be seen, that by the use of this device, a cow or other animal, however badly disposed, cannot jump over or break down a fence of ordinary height, as, when she approaches the fence nearer than the length of the pokes, the latter will come in contact therewith, and force the block, with its brads, backward against the breast of the animal, which will

cause her, under ordinary circumstances, to "haul in her horns," and desist from the undertaking.

The arrangement is attached in the following manner:

The key is removed from the yoke, which is placed over the head of the animal, the head *a'* is inserted in one of the slots of the bow, and turned half round, which brings the main part of the key in a position to be inserted, which is then done, and the key pushed across the bow until it reaches the opposite side.

The neck *a²* is then near the slot, and by springing the bow slightly, it is inserted therein, which enables the key to be again turned, and the head *a'* forced through the opposite slot; both the necks *a²* and *a³* will be in their respective slots, and by turning the key once more, the head *a⁴* will act as a button, and confine the key somewhat sprung together; the head being longer than the slots, cannot pass through.

I am aware that devices of the sort have been patented containing one poke, but I claim superior advantages by the use of two, which are, that a greater length of fence is protected, as the liability to miss the same is decreased one-half, and being situated at the ends of the block, they will not interfere with the feeding of the animal, which is well known to be the case when but one poke is employed.

Having thus fully described my invention,

What I claim as new, and desire to secure by Letters Patent, is—

The key *a*, constructed as described, when combined with the yoke *A*, in the manner and for the purpose set forth.

This specification signed and witnessed, this 29th day of March, 1869.

J. L. W. TOWNSEND.
